BOILER FEED WATER REGULATING APPARATUS

Joseph M. Barrett, Cleveland Heights, Ohio, assignor to Bailey Meter Company, a corporation of Delaware

Application August 6, 1930, Serial No. 473,459

6 Claims. (Cl. 122—451.2)

This invention relates to regulating apparatus for the feeding of water to steam generating boilers, and in particular to provide an arrangement whereby water will be fed to the boiler at the proper rate for efficient and safe operation.

Such boilers commonly have one or more drums in an upper part of the assembly, for water storage. One or more of these drums are usually only partly filled with water, thus providing a steam liberating surface. To the steam space so formed, the steam outlet pipe is connected, and it is important that the level of water be so maintained that with steam leaving the boiler at high velocities, water is not carried out in slugs or otherwise with the steam. It is equally important that the level be not lowered to a point where burning of the parts would occur due to being exposed to high temperatures without heat conducting liquid on the other side of the metal.

For a definite weight of water in the boiler the location in elevation of the steam liberating surface, commonly termed the drum level, will vary widely with changes in rating due to "swell" or the effect of the percentage of steam bubbles below the surface of the water. Immediately upon an increase in rate of steam generation the water in the boiler will swell up, raising the drum level appreciably, and it has been almost universally the operation of feed water regulators to immediately pinch down on the rate of feed until the increased rate of evaporation in the boiler has used water from the storage total to an extent that the level within the drum drops from its swelled position not only to its original level but to a lower level corresponding to the new rate of steam generation, sufficient to open up the feed water regulator an amount whereby water will be supplied at a rate corresponding to the new rate of output.

By so allowing the water in the boiler drum to evaporate down to a minimum level before the feed water regulator opens further and admits water at a rate commensurate with the new rate of steam generation, a lag in water inflow compared to steam outflow is introduced which is oftentimes serious considering the small storage available for water. High pressure design dictates from a cost standpoint the use of small water storage drums containing possibly only 10 to 20% of the total water of the boiler. Such conditions mean that at a high rate of steam generation the water stored in the boiler drum is sufficient to last only a minute

or a fraction thereof, so that if the feed of water to the boiler is interrupted or not in step with changes in steam output, the water stored in the drum will be used up and serious damage might result.

The primary object of my invention is to provide an improved construction and arrangement for controlling the supply of feed water to a boiler whereby the supply is controlled from factors indicative of the usage and of the total weight or mass of water in the boiler, rather than from factors indicative of drum level, which as pointed out above, is affected not only by usage but also by swell.

A further object of my invention is to maintain the level of water in the boiler drum within safe limits while allowing it to vary with varying rates of operation.

Another object is to provide means for feeding water to the boiler in accordance with the usage, to keep a definite weight of water in the boiler.

Other objects of the invention are in part obvious and in part will appear more in detail from the description hereinafter.

In the drawings Fig. 1 represents diagrammatically one arrangement of feed water regulating apparatus embodying the invention.

Fig. 2 is a sectional view of part of a regulating valve.

Figs. 3 to 9 inclusive represent graphically, relations between various factors in my invention.

Referring to the drawings, 1 indicates conventionally a steam boiler comprising upper and lower drums connected by boiler tubes 1a. Connected to an upper drum is a conduit which leads through a superheater 3 to a discharge conduit 4, and connected to an upper drum is a feed water supply conduit 2. Conduit 2 is shown in part on a large scale in order to illustrate better the construction of certain parts. The structure so far described is to be taken as typical of any suitable boiler structure.

In the embodiment being described, is illustrated a valve means located in the conduit 2 controlling the admission of water to the boiler and comprising a flow regulating valve 11 and a pressure controlling valve 12. When the flow regulating valve is held at a constant opening and the pressure controlling valve maintains a constant pressure at the inlet to the flow regulating valve, then water will be fed to the boiler at a constant rate. However, according to my invention, the pressure controlling valve maintains ahead of the flow regulating valve, a pressure

varying with rate of steam generation in the boiler, which for a constant opening of the flow regulating valve, results in an admission of water to the boiler directly proportional to the rate of steam generation. However, due to leakage or other causes, the weight of water in the boiler may gradually increase or decrease, and I readjust the amount of opening of the flow regulating valve to compensate for the change in weight of water in the boiler.

As an indication of variation in the total weight of water in the boiler, I have found that the level in a cold water leg of a U-tube, of which the boiler proper forms the hot water or other leg, is the most satisfactory. Referring to Fig. 1, the pipe 6, external to the boiler, is connected to the lowest chamber of the boiler and by the joining pipe 7, to the steam space of an upper drum. A U-tube joined at the upper ends on account of the pressure in the boiler, is thus formed. The level of water within the boiler, indicated at A, is subject to swell, ebullition and entirely different temperature-density conditions than is the level indicated at B, in the communicating pipes 6 and 7 external to the boiler. Normally the water level B is lower than the level A, except when the boiler is cold, at which time the temperatures being uniform throughout the system, levels A and B will be the same. Water level B is unaffected by swell, varies only with usage, and is therefore indicative of the weight of water in the boiler as a whole.

As a means of operating the flow regulating valve 11, responsive to variations in the water level B, indicative of weight of water in the boiler, I employ a trapped vapor-generating system, comprising a generator indicated generally at 5, connected by a pipe 17 to an expansible metal bellows 16 mounted on the valve 11, in a manner to position the valve parts and regulate the passage area for flow through the valve. The generator 5 comprises a pipe 8 joined to and in communication with the pipe 6, lying across or spanning inclinably the normal water level B in the pipe 6, and surrounded by a trapped annular chamber 9a as enclosed by a pipe 9 provided with fins for heat radiation and closed at the ends by flanges 10. The trapped chamber 9a contains a vaporable liquid such as water in contact or suitable heat-conducting relation with pipe 8 which has normally a water level B corresponding with the water level in pipe 6.

Steam in the pipe 8 above the water level B, by heat transfer causes a vaporizing of some of the liquid in the chamber 9a, creating a pressure effective upon the remainder of the liquid in the chamber 9a, acting upon the expansible metal bellows 16 through the connecting pipe 17. A state of equilibrium is reached in the trapped generating system when the level of liquid within the annular chamber 9a corresponds to the level in the pipe 8, through vaporization, and the resulting pressure having transferred some of the trapped liquid to the expansible metal bellows 16, causes a movement of its abutment 15, which movement is resisted by a spring 14.

To the movable abutment 15 of the motive bellows 16 is connected the valve stem 13 and movement of the abutment results in movement of the valve stem 13 to vary the passage opening through the valve 11. The passage area for flow through the valve 11 is thus varied in accordance with variations in a water level existing in the pipe 6, indicative of the weight of water in the boiler.

To control the pressure of the water entering the flow regulating valve 11, I provide a valve means 12 located in the conduit 2 at the inlet to the valve 11. The pressure of the water entering the valve 11 is controlled through the throttling action of valve discs fastened to a stem 18 and positioned relative to their seats in the valve 12. The stem 18 is fastened to and operated by a piston 20 movable in a suitable cylinder part of the valve 12, the piston 20 being subjected to the pressure of the water at the inlet to valve 11 on its upper side and the pressure existing in the boiler 1 on its lower side. To transmit to the piston 20 a pressure representative of that in the boiler 1, is shown a pipe 21 connected by the pipe 7 to an upper drum of the boiler, and having a condensation chamber 22 located at the highest point of connection so as to provide a definite static water head.

It is necessary that the pressure of the water entering the valve 11 be greater than the pressure in the boiler, otherwise water would not enter the boiler. Furthermore, some frictional loss of pressure will occur in the passage of the water through the passage-area of the valve 11. To control the pressure of the water entering the valve 11, a spring 19 is provided, acting against a lever support 27 at the one end and effective on the stem 18 at the other end to urge the stem and valve discs away from the valve seats, in the same direction of force as the boiler pressure acts on the piston 20. For a fixed position of the lever support 27, the valve discs are urged away from their seats by the effect of the spring 19 plus the force of the boiler pressure on the piston 20, and are urged toward their seats by the force of the water pressure at the outlet of the valve, acting on the other side of the piston 20. The spring 19 then forms a calibrating measure of the pressure differential which will exist between the pressure in the boiler and the pressure of the water entering valve 11, the tendency being to always supply water at a constant excess over boiler pressure.

In order that the feed of water to the boiler shall be directly proportional to the rate of steam generation or boiler output I provide in connection with the valve means 12, a further arrangement of parts, responsive to a function of boiler output, for varying the effect of the spring 19 and correspondingly varying the excess of pressure of the water entering the valve 11 over the pressure in the boiler.

To vary the effect of the spring 19 is provided a means for moving its support, namely the lever 27, so that for any given position of the valve stem 18, the spring will be more or less compressed and exert a greater or lesser force tending to move the valve stem. The lever 27 is pivoted between its ends and at the end opposite that supporting the spring 19, is connected to a rod 26, having an adjustment, illustrated as a turnbuckle 29, for length. To the lower end of the rod 26 is fastened the movable abutment 25 of an expansible metal bellows 24 which is subjected to a pressure differential varying in a known manner with rate of steam generation.

The pressure which is effective on the outside of the bellows 24 is that of the boiler 1 transmitted through the pipes 7 and 21, while that effective on the inside of the bellows 24 is that of the steam outlet conduit 4, transmitted through the pipe 23. The difference between these two pressures is that lost by the steam in its passage from the boiler drums, through the superheater 75.

3 to the outlet conduit 4 and this pressure loss or differential varies in a known manner with rate of steam flow. The pressure differential effective upon the bellows 24 and upon the loading of the 5 spring 19 bears, then, a definite relation to boiler output.

For the valve means 12 I have provided various adjustments to take care of changes in operating or other conditions. At 28 is indicated a 10 stop threaded through the casing, providing an adjustable limit to the travel of the piston 20 and through the stem 18 of the valve discs relative to their seats. By adjustment of the screw 28 upwardly toward the piston 20 the travel of the piston 15 ton will be so limited in the one direction that the valve may have any desired minimum opening to protect against completely shutting off the flow of water supplying the valve 11. Adjustable means indicated at 29 as a turnbuckle may be used to vary the length of the rod 26 and change the initial loading of the spring 19 and correspondingly the effect of the function of boiler output upon the loading of the spring 19. At 20 30 I have indicated a stop threaded through the 25 casing, adjustable to limit the travel of lever 27 whereby the minimum loading of the spring 19 may be varied.

The movable abutment 25 of the bellows 24 is mechanically limited in its travel in an upward 30 direction by the casing of the pressure differential valve 12 and in a downward direction by a stop 31. The hand adjustment illustrated at 29 as a turnbuckle then serves to shorten or lengthen the connecting link 26, thereby increasing or decreasing 35 the compression of the spring 19 and correspondingly loading or unloading the differential pressure valve 12. By this means a limit may be set to the lowest excess pressure which can exist across the two sides of regulating valve 11. 40 The adjustable stop 28 not only provides for limiting the travel of the valve stem 18 in a manner such that the valve can never be closed below a predetermined amount as controlled by the position of the stop 28, but also provides a hand 45 means of opening the valve to any desired position regardless of pressure conditions throughout the system. The valves on stem 18 are permitted to seat and close off, if the adjustable stop 28 is backed downwardly out of the way. The adjustable stop 30 acting against the lever 27 provides a means for limiting the unloading effect on the 50 spring 19 and providing hand adjustment below the limit encountered when the movable abutment 25 of the bellows 24 comes against the casing of the pressure valve 12.

I have described in detail the component parts and mechanisms illustrated in Fig. 1 and in accordance with the present embodiment of my invention they are preferably located in definite relation to each other and the boiler. For instance, I prefer to locate the pressure control valve 12 in the conduit 2 at the inlet side of the flow regulating valve 11. I have shown and described the spring 19 of the valve means 12 as being located 60 in accordance with a pressure differential which is obtained across the superheater 3 but I might equally as well insert an orifice or other pressure differential producing device in the conduit 4. Likewise, the generator 5 is shown at a certain 65 inclination across the water level B in the pipe 6 whereas it might under certain conditions be desirable to incline it more or less or move it up or down relative to the pipe 6.

The relation (due to swell) between the water 70 level A and the rate of steam generation, assum-

ing a constant weight of water in the boiler, is approximately parabolic in function. The actual location in elevation and inclination of the generator 5 across the level B is determined by the limitations of drum size and allowable or desirable change in the level A with variations in rate of steam generation. 5

It may be desirable to allow a relatively low level A to exist at low rates of steam output so that upon a sudden or appreciable increase in the 10 rate of output the level will not go to a dangerous height and conversely, to have a high level A at high rates of steam output so that upon a sudden and appreciable decrease in rate of output, the level will not fall to a dangerous low point. 15

The feed water regulators now common in which the valve is positioned from level A affected by swell, are in effect geared to level. That is, there is a definite level A and a definite valve position for each rate of steam generation, 20 and not only will these levels vary with a different excess pressure across the valve opening, but for equal increments of rate of steam generation, there will be unequal increments of change in level A due to the characteristic of the 25 swell relation. Further, equal increments of valve stem travel may not result in equal increments of flow of water through the valve.

With my invention I provide for the feeding of water to the boiler in accordance with the usage, 30 and tending to keep a definite weight of water in the boiler. My invention is responsive to variations in a level which is unaffected by swell, and to a factor indicative of rate of usage.

In operation, assume a definite rate of steam 35 generation in which, for example, level A exists approximately at the center line of the drum as shown, and level B at the center line of the inclined generator 5. The flow regulating valve 11 and the pressure controlling valve 12 have a certain assumed open position, and water is being fed to the boiler. I will now describe the effect of an increase in the rate of steam generation or 40 boiler output.

The immediate effect due to swell through 45 lowering of the pressure in the steam space above level A is a rise in the level A. The level B is, however, unaffected by swell and varies only as the total weight of water in the boiler changes from discrepancy between input and output, or 50 from losses such as blowdown, blowing of the safety valves, leakage, etc.

I have in the flow regulating valve 11 two variables responsible for changes in the rate of feed of water to the boiler, first the passage-area, and 55 second the differential pressure impressed across the valve, resulting in flow through the passage-area.

The first is controlled or varied by movement 60 of the valve stem 18 in accordance with changes in level B indicative of weight of water in the boiler, or discrepancy between input and output. An important feature of my invention is that I so shape the ports 11a (Fig. 2) that for a given 65 excess pressure, equal increments of valve stem motion will result in equal increments of flow. This shaping takes into account passage-area, coefficients of flow, constants, eddy currents, the shape of the valve passages and other variables, and should preferably be done by experiment for 70 different sizes or designs of valves. I may if desired so shape the ports or passages that the relation between equal increments of valve stem motion and increments of flow may be direct, inverse, or as any desired function. 75

In Fig. 9 I have plotted a straight line relation between valve stem position and water flow, the relation which exists in the preferred form of my invention wherein equal increments of movement of the stem 13 of the regulating valve 11 result in equal increments of water flow for a given excess pressure across the valve 11. This is accomplished by so shaping the ports or passages 11a that a relation as shown in Fig. 7 between valve 5 stem position and passage-area will result in the relation shown in Fig. 8 between water flow and passage-area, in turn giving the straight line relation of Fig. 9. The curves Fig. 7 and Fig. 8 are drawn of arbitrary shape and are preferably obtained by experiment. The curve of Fig. 9 results 10 from those of Fig. 7 and Fig. 8 as Figs. 7 and 8 are of the same shape and incremental value.

The second variable, the excess pressure, I control to give a flow of water directly proportional to the rate of steam generation or boiler output. For a given passage-area the water flow will vary directly as the square root of the excess pressure across the regulating valve 11. The excess pressure is controlled directly by the loading 15 of the spring 19 through the action of the expansible metal bellows 24 acted upon by the differential pressure or drop in pressure of the steam flowing through the superheater 3. This differential pressure varies as the square of the 20 rate of steam flow so that water flow (for any given passage-area in the regulating valve 11) will be directly proportional to the rate of steam 25 output.

In Fig. 3 I have plotted the relation existing 30 between flow and pressure drop, in which the rate of flow of steam through the superheater varies as the square root of the pressure drop. Fig. 4 is a similar curve of the relation existing across 35 the regulating valve 11 for a given passage-area in which the rate of flow of water through the given passage-area varies as the square root of the excess pressure across said passage-area.

Inasmuch as the pressure drop through the superheater is applied through the bellows 24, the 40 movable abutment 25, link 26 and lever 27 to load the spring 19 which is coacting with the piston 20 in positioning the valve discs relative to their seats in the pressure controlling valve 12 to control the pressure of water at the inlet to the regulating valve 11 relative to boiler pressure 45 at the outlet side of the regulating valve 11, and thus control the differential pressure across the given passage-area in regulating valve 11, then the relation existing between pressure drop 50 through the superheater and the differential pressure across the regulating valve as plotted in Fig. 5 as a straight line holds true.

With the differential pressure across the regulating valve 11 directly proportional to the pressure drop through the superheater, which in turn varies as the square of the rate of steam flow and itself varies as the square of the rate of water flow, then the relation between steam flow and water flow as plotted in Fig. 6 is a straight line.

I have then a regulating valve 11 through which the flow of water will vary directly in accordance 60 with changes in weight of water in the boiler as well as directly with the rate of steam generation.

If then the rate of steam output is increased 65 there will be an immediate change in the rate of feed of water to the boiler through a change in excess pressure. The increased flow of steam through superheater 3 will result in a change 70 in the pressure drop, and this will be reflected 75

through conduits 7 and 21 to one side of the bellows 24 and through conduit 23 to the other side of the bellows 24, causing a change in the position of the movable abutment 25 which through the intermediary of the rod 26 and the fulcrumed lever 27 varies the loading on the spring 19 resulting in a change in the pressure of the water at the inlet to the regulating valve 11 relative to the pressure in the boiler 1 on the outlet side of the regulating valve 11. As explained before, the flow through the fixed passage-area of the regulating valve 11 will vary directly with the change in the rate of steam generation.

Now assuming that leakage or discrepancy between the input and outflow results in a change in the weight of water in the boiler, this will be reflected by a change in the level B in the inter-communicating conduit system comprising conduits 7, 8 and 6. With the level B in conduit 8 gradually sinking, for example, through the using up of stored water, a greater steam zone comes in contact with the liquid trapped in chamber 9a, additional liquid is vaporized and the increase in pressure so generated acting through 25 the connecting conduit 17 on the bellows 16 operates to open the regulating valve 11 somewhat or change its passage-area. Inasmuch as the valve ports or openings are in this embodiment so designed that equal increments of valve stem 30 travel will result in equal increments of flow, then for a constant differential pressure across the passage-area an increased flow of water will result, directly proportional to variations in the level B which is indicative of changes in the 35 weight of water in the boiler as a whole.

I have then to all intents and purposes a regulating apparatus which is responsive to a level unaffected by swell for obtaining the valve opening, and at said valve opening has impressed upon 40 it a pressure differential varying as a function of the rate of steam generation or boiler output, controlling to maintain a definite weight of water in the boiler system.

I have illustrated and described one embodiment 45 of my invention, but it is expressly understood that by so doing I have not limited my invention other than as stated in the claims in view of prior art.

What I claim as new and desire to secure by 50 Letters Patent of the United States, is:—

1. In combination, a boiler, a conduit for supplying liquid to the boiler, a conduit through which vapor is discharged from the boiler, a valve in the supply conduit, means responsive to variations in an indication of the weight of water in the boiler for positioning said valve, a second valve in said conduit in advance of said first-named valve, and means responsive to the rate of flow of vapor from the boiler for positioning said second-named valve, said second-named valve controlling the pressure at the inlet to the first-named valve proportional to a function of the said rate of flow of vapor.

2. A boiler, a feed water regulator, a generator controller therefor comprising a conduit connected to and spanning in elevation the entire boiler and a trapped generator chamber containing a vaporable liquid located to be responsive to variations in an indication of the weight of water in the boiler, and means responsive to a function of boiler output to vary the pressure differential across said regulator.

3. In combination, a boiler, a feed water regulator therefor, control means for said regulator

responsive to variations in an indication of the weight of water in the boiler, and means responsive to the rate of flow of steam from said boiler to vary the pressure of the water supplied to said regulator.

4. A boiler, a feed water regulator, a controller therefor responsive to variations in the weight of water in the boiler, and means responsive to a function of boiler output to vary the pressure differential across said regulator.

10 5. In a boiler feed water regulator, means responsive to variations in the weight of water in the boiler for varying the passage-area of the regulator, and means responsive to a function

of steam outflow to vary the pressure differential across said regulator.

6. A boiler, a feed water regulator therefor having means for varying the area of the flow passages therethrough, said means responsive to variations in the weight of water in the boiler, the flow passages so proportioned as to result in a definite relation between increments of regulating motion and increments of flow, and a differential pressure regulator responsive to a function of the rate of steam outflow for controlling the pressure drop across said regulator valve.

JOSEPH M. BARRETT.
